UNITED STATES PATENT OFFICE.

JAMES FINEGAN, OF HAVERSTRAW, NEW YORK.

IMPROVEMENT IN BRICK-PRESSES.

Specification forming part of Letters Patent No. 39,906, dated September 15, 1863.

To all whom it may concern:

Be it known that I, JAMES FINEGAN, of Haverstraw, in the county of Rockland and State of New York, have invented a new and useful Improvement in Brick-Presses; and I do hereby declare that the following is a full, clear, and exact description of the same, reference being had to the accompanying drawings, making a part of this specification, in which—

Figure 1 is a vertical section of my invention, taken in the line *xx*, Fig. 2; Fig. 2, a vertical section of the same, taken in the line *yy*, Fig. 1.

Similar letters of reference indicate corresponding parts in the two figures.

This invention relates to an improvement in that class of brick-presses in which a reciprocating plunger is used for compacting the clay in the molds or compressing it therein.

The invention consists in forming the plunger-rod of two parts, connected together and arranged in such a manner that the stroke of the plunger may be varied at pleasure, and the pressure thereof consequently regulated as desired.

To enable those skilled in the art to fully understand and construct my invention, I will proceed to describe it.

A represents the clay-box or receptacle of a brick-press, and B the press-box from which the clay is forced into the molds. C is the plunger, which works in the box B, and D the plunger-rod, which is formed of two parts, *a b*, connected together by a pin, *c*, which passes tightly through the lower part of *a* and through an oblong slot, *d*, in the upper part of *b*. (See Fig. 2.) The lower part of *a* is slotted longitudinally, as shown at *e*, to receive the upper part of *b*, as shown in Fig. 1, and within the slot *e* there is fitted a slide, *E*, against which a pin, *f*, in the part *a* of the rod *D* bears when the

plunger descends. The pin *f* may be inserted in any one of a number of holes, *g*, in the part *a* of the plunger-rod, and by this means the stroke of the plunger may be varied (increased or diminished) as desired. When the slide *E* is adjusted so as to be in close contact with the upper end of the part *b* of the plunger-rod, the plunger *C* will have a length of stroke equal to the length of the crank *F*, which operates the plunger, but if the pin *f* be inserted in a more elevated hole, *g*, so as to admit of the play of the slide *E* between the upper end of the part *b* of the rod *D* and the pin *f*, the stroke of the rod *D* will be diminished in a degree corresponding to the play allowed the slide *E*. Hence it will be seen that the pressure of the plunger *C* on the clay may be regulated as desired by simply shifting the pin *f*. Thus, by this simple device, which will not add in an appreciable degree to the cost in the construction of the press, a very important result is attained, for the clay, in being forced into the molds, requires to be subjected to a greater or less pressure, according to the degree of moisture it contains—technically speaking, according to its “stiffness.”

Having thus described my invention, what I claim as new, and desire to secure by Letters Patent, is—

The plunger rod *D*, composed of two parts, *a b*, one part, *a*, having a pin, *c*, passing tightly through it, which pin passes through an oblong slot, *d*, in the other part, *b*, in combination with the slide *E*, fitted in the slot *e* of the part *a* of the plunger-rod, and the adjustable pin *f*, all arranged as and for the purpose specified.

JAMES FINEGAN.
